UNITED STATES PATENT OFFICE.

ALEXANDER B. TAPPEN, OF OSSINING, NEW YORK.

REINFORCEMENT FOR CONCRETE COVERINGS.

1,255,244.

Specification of Letters Patent.

Patented Feb. 5, 1918.

Application filed March 6, 1914. Serial No. 822,846.

To all whom it may concern:

Be it known that I, ALEXANDER B. TAPPEN, a citizen of the United States, and a resident of Ossining, Westchester county, 5 and State of New York, have invented certain new and useful Improvements in Reinforcements for Concrete Coverings, of which the following is a specification, reference being had to the accompanying drawings, forming a part thereof.

My invention relates to improvements in expandable reinforcements for concrete and the like, of the type which has been invented by David Homer Hayden and for which he 15 has made application for Letters Patent, and its object is to improve upon reinforcements of this kind which are compact as an article of manufacture and easily packed and transported and which are adapted to 20 be expanded into engaging relation with the flange of a steel member.

The reinforcement of the type to which this invention applies comprises a series of cross-stays or members which are so connected 25 that the reinforcement is capable of being expanded longitudinally of the beam or structural member to which it is applied, and of being contracted laterally thereof, the cross-stays or members being bent at 30 predetermined intervals to form hook portions which engage the opposite edges of the flange of the structural member when the reinforcement is thus laterally contracted. The extent of longitudinal expansion 35 and lateral contraction are both limited by the width of the flange to which the reinforcement is applied.

The projections which hook over the edges of the flange are so arranged as to 40 space the cross-stays from the adjacent surface of the flange in order to leave a body of cement between them and the flange. It has been found however, that when such reinforcement is applied to I-beams with wide 45 flanges, the outward pressures exerted by the edges of the flange upon the portions which hook over the flanges, cause the cross-stays to buckle or bend toward the surface of the flange so that the required distance 50 between the flange and the cross-stays is not maintained. But with reinforcement made according to this invention no such trouble can occur.

Another trouble with expansions of this 55 type has been that they are not sufficiently rigid to prevent blows on one side bending

the parts so as to lessen the hold of the expansion on the opposite side of the beam. I have devised a simple way of overcoming this difficulty and at the same time making 60 the expansion capable of supporting greater weights.

These and other advantages of my invention will appear in the following specification in which I will describe the invention, 65 the novel features of which will be set forth in appended claims.

In order that this invention may be understood, reference is made to the accompanying drawings of which Figure 1 is a 70 transverse sectional elevation of the lower part of a beam of structural iron, below which is shown a reinforcement in its folded or contracted state, or in the condition in which it is manufactured and shipped.

Fig. 2 is a corresponding view of the I-beam with the reinforcement expanded and applied to its lower flange, together with a body of concrete or cement which surrounds the beam and which is supported 80 thereon by the reinforcement and one of the mold boards under the body of concrete.

A bottom plan view of an I-beam is shown in Fig. 3 with some of my improved reinforcement. Some of this reinforcement is 85 shown in contracted form and some of it expanded into engagement with the flange. This view clearly illustrates the lateral contraction of the reinforcement which occurs when it is expanded longitudinally.

Fig. 4 is an isometric perspective of a portion of the expanded reinforcement shown in the other figures.

In Figs. 5, 6 and 7 I have shown three modifications of a detail of construction.

Figs. 8 and 9 are respectively an elevation and a plan view of a portion of the device made in a somewhat different manner.

Fig. 10 is a perspective view of a still 100 further modification of the invention.

Like characters of reference designate corresponding parts in all the figures.

10 designates the cross-stays which may be made of wire which are alternately connected with one another at spaced intervals in some suitable manner, preferably by being welded to connecting pieces 11. By welding the connecting pieces 11 to the wire cross-stays, the cross-stays are annealed and 105 softened adjacent to the weld and consequently when the reinforcement is expanded.

the bends in the wire come at the point of connection and the portion of the cross-stays between the points of connection are straight.

5 Another advantage in this arrangement arises from the fact that it is only necessary to exert a pull at opposite ends of the reinforcement in order to expand it uniformly.

Outside of each connecting piece the end 10 of one of the wires is bent upwardly as at 12 to form a stop projection. The other end of this same wire extends beyond an opposite connecting piece as at 13, at the end of which projection it is bent upwardly as at 15 14; then inwardly to form the supporting hook 15, then up, out and down to the point 16. From this point 16 it runs down to the connecting piece 11 to which it is attached and thence it extends downwardly to form 20 another stop projection 17. The portion 18 between the point 16 and the connecting piece 11 then forms a brace or support.

In Figs. 1-5 this brace is shown as fastened to the connecting piece 11 by welding, 25 which is the usual construction, but in Fig. 6 its end is shown as wound around the connecting piece.

In Fig. 7 it is wound around the connecting piece 11 but its end extends upwardly as 30 at 17^A. When this form of construction is used, the stop projections 12 of course may be bent downwardly instead of upwardly so as to have a stop projection above and below each connecting piece.

35 Before describing the modification shown in the remaining figures of the drawings, I will point out the operation and advantages of this device.

When the reinforcement is applied to the 40 flange of an I-beam by being pulled out longitudinally, the outward lateral pressures have a tendency to make the parts thereof which are spaced from and substantially parallel with the outer surface of the flange, 45 bend or buckle inwardly toward the flange so that the desired amount of space between the flange and the reinforcement is diminished. The upwardly extending stop projections 12 (or 17^A) prevent such buckling 50 to any undesirable extent by coming in contact with the flange.

Another advantage is that the brace 18 makes the reinforcement capable of sustaining greater weights. Furthermore as 55 the braces are affixed to the connecting pieces 11, it makes the structure more rigid and prevents any inward lateral pressure upon the part 14 forcing the hooks 15 off from the opposite edge of the flange.

60 The stop projections 17 may be used as spacers to hold the mold board 19 at the desired distance from the beam.

Further rigidity may be given to the device by making an additional twist 20 in the 65 wire between the parts 13 and 14 and as

shown in Figs. 8 and 9 these twisted portions may extend laterally beyond the rest of the reinforcement so that they may be used as spacers for the side mold boards.

In Fig. 10 another way of stiffening and 70 strengthening the reinforcement is shown. In this case the parts 10, 13, 14, 15 and 18 are bent as before and similarly affixed to the connecting pieces 11, and the end 17 bent downwardly as at 17 or upwardly as at 17^A. 75 But instead of the other end of the wire terminating in a short-stop projection 12 as in Fig. 4, it is extended upwardly as at 21 in a direction parallel with the brace 18 to form another brace and then up and over as at 80 22-23 to form another hook for engaging the flange of an I-beam.

It is obvious that the reinforcing material shown and described may be made in different forms and of various materials, and I 85 intend no limitations other than those of the appended claims.

What I claim is:

1. A concrete reinforcement comprising a plurality of transverse wires bent to form 90 portions adapted to hook over the edges of a flange and alternately disposed connections between adjacent wires alternating in respect of the longitudinal center of the reinforcement, each of said wires forming 95 a brace from the flange to an adjacent connection and being secured thereto.

2. A concrete reinforcement comprising a plurality of transverse wires bent to form 100 portions adapted to hook over the edges of a flange and alternately disposed, and connections between adjacent wires alternating in respect of the longitudinal center of the reinforcement, the end of the wires being continued from the hook portions around 105 the flange to adjacent connections and being secured thereto.

3. A concrete reinforcement comprising a plurality of transverse wires bent to form 110 portions adapted to hook over the edges of a flange and alternately disposed, and connections between adjacent wires alternating in respect of the longitudinal center of the reinforcement, the end of the wires extending from the hook portions to adjacent connections and extending beyond the connection to form stop projections.

4. A concrete reinforcement comprising a plurality of transverse wires, hooks formed of bends in said wires adapted to hook over 120 the edges of a flange, and stop projections formed by the ends of said wires, said wires being alternately disposed; welded connections between adjacent wires alternating in respect of the longitudinal center of the reinforcement, and braces formed of portions of the wires intermediate the hooks and adjacent connections secured to said connections.

5. A concrete reinforcement comprising a 130

plurality of transverse wires bent to form portions adapted to hook over the edges of a flange and alternately disposed, and to form stop projections at each connection,
5 connections between adjacent wires alternating in respect of the longitudinal center of the reinforcement, and a brace from the hook portion of the wire to an adjacent connection and extending beyond the connections to form other stop projections,
10

6. A concrete reinforcement comprising a plurality of transverse wires bent to form portions adapted to hook over the edges of a flange and alternately disposed, and to form stop projections at each connection,
15

connections between adjacent wires alternating in respect of the longitudinal center of the reinforcement, and a brace from the hook portion of the wire to an adjacent connection and extending beyond the connections to form other stop projections; and twisted portions extending laterally beyond the hook portions.

In witness whereof I have hereunto set my hand in the presence of two subscribing 20
witnesses, this 5 day of March 1914.

ALEXANDER B. TAPPEN.
